F. A. MANCHESTER.
SHUTTLE FOR WEFT REPLENISHING LOOMS.
APPLICATION FILED DEC. 2, 1913.

Patented June 2, 1914.

UNITED STATES PATENT OFFICE.

FRED ARNOLD MANCHESTER, OF HOPEDALE, MASSACHUSETTS, ASSIGNOR TO DRAPER COMPANY, OF HOPEDALE, MASSACHUSETTS, A CORPORATION OF MAINE.

SHUTTLE FOR WEFT-REPLENISHING LOOMS.

1,098,744.

Specification of Letters Patent.

Patented June 2, 1914.

Application filed December 2, 1913. Serial No. 804,196.

To all whom it may concern:

Be it known that I, FRED ARNOLD MANCHESTER, of Hopedale, in the county of Worcester and State of Massachusetts, have 5 invented a new and useful Improvement in Shuttles for Weft-Replenishing Looms, of which the following is a specification.

The present invention relates to a spreader employed to maintain in proper relative 10 position the holding jaws of the shuttle spring which is employed in automatically threading shuttles for the purpose of yieldingly grasping the head of the bobbin or other analogous weft carrier.

15 The improvement is illustrated in the accompanying drawings, in which—

Figure 1, is a plan view of the weft carrier holding end of a shuttle, parts being broken away to facilitate the illustration.

20 Fig. 2, is a longitudinal vertical section of the same end of the shuttle. Fig. 3, is a cross-section. Fig. 4, is an enlarged horizontal section in the plane indicated by the line 4—4 in Fig. 2.

25 The improved spreader is intended to keep in proper position the two jaws of the weft-carrier holding shuttle spring when the jaws are bent from a single piece of sheet metal so that the jaws are maintained 30 at the proper distance apart to receive an automatically inserted weft-carrier and to securely hold the same in place. Such a shuttle spring is illustrated in the accompanying drawings, wherein—

35 A, is the shuttle, B, is the shuttle spring, and C, is the guard. The shuttle spring has resilient jaws a, a, and a shank consisting of two connected legs b, b, which fit snugly within a recess in the body of the 40 shuttle. The guard C, embraces the shank of the shuttle spring and is maintained in place by a screw D. The shuttle spring is held in place by means of the guard and a transverse bolt E, passing transversely 45 through both legs of the shank. In all of the respects just described, the shuttle spring and its guard are similar to corresponding parts shown in United States Letters Patent of Stimpson, No. 1,074,662, 50 October 7, 1913.

The present improvement resides in the shuttle spreader F, which is a vertical bolt passing through apertures in the upper and lower plates c, and d, of the shuttle guard.

The lower end only of this bolt is screw-threaded and this screw-threaded end fits within a nut G, which is seated within a socket in the bottom of the shuttle body. The conical head of the bolt seats within a conical aperture in the top plate c, of the spreader so that the upper surface of the bolt head is flush with the upper surface of the guard. This spreader extends vertically between the legs b, and b, as shown in Fig. 4, and its cylindrical body fits tightly 65 against the facing surfaces of said legs. There is no lost motion between the spreader and the legs of the shuttle spring shank and, consequently, the free jaws a, a, of the shuttle spring are held the proper distance 70 apart so that they cannot approach each other sufficiently to prevent the ready entrance of the head of the automatically inserted weft-carrier.

The spreader has a nick in its head to receive a screw-driver for the purpose of inserting and withdrawing the spreader from its nut G.

I claim—

1. A shuttle for weft replenishing looms 80 having a shuttle spring with a shank consisting of separated legs fitting within a recess in the shuttle body, a guard having upper and lower plates embracing the shank of the shuttle spring, said upper and lower 85 plates having apertures that in the upper plate being conical, a spreader consisting of a vertical bolt whose cylindrical body fits tightly between the legs of the shuttle spring shank said bolt passing through the apertures in the upper and lower plates of the guard, said bolt having a conical head fitting within the conical aperture of the upper plate of the guard and being screw-threaded at its lower end, and a nut located 90 within a socket in the bottom of the shuttle 95 into which the lower end of the bolt screws.

2. A shuttle for weft replenishing looms having a shuttle spring with a shank consisting of separated legs fitting within a 100 recess in the shuttle body, a guard having upper and lower plates embracing the shank of the shuttle spring, said upper and lower plates having apertures, a spreader consisting of a vertical bolt fitting tightly between 105 the legs of the shuttle spring shank and passing through the apertures in the upper and lower plates of the guard, and a nut lo-

cated within a socket in the bottom of the shuttle into which the lower end of the spreader bolt screws.

3. A shuttle for weft replenishing looms having a shuttle spring with a shank consisting of separated legs, a spreader consisting of a vertical bolt fitting tightly between the legs of the shuttle spring shank, and a nut located within a socket in the bottom of the shuttle into which the lower end of the spreader bolt screws.

4. A shuttle for weft replenishing looms having a shuttle spring with a shank consisting of separated legs, a guard having upper and lower plates embracing the shank of the shuttle spring, said upper and lower plates having apertures in the upper plate being beveled, and a spreader fitting tightly between the legs of the shuttle spring shank and passing through the apertures in the upper and lower plates of the guard.

5. A shuttle for weft replenishing looms

having a shuttle spring with a shank consisting of separated legs, a recess in the shuttle body, a vertically extending spreader 25 consisting of a vertical bolt fitting tightly between the legs of the shuttle spring shank and passing through the apertures in the upper and lower plates of the guard, said spreader having a beveled head fitting with 30 in the beveled aperture of the upper plate of the guard and being screw-threaded at its lower end, and a nut located within a socket in the bottom of the shuttle into which the lower end of the spreader bolt 35 screws.

In witness whereof, I have hereunto signed my name in the presence of two subscribing witnesses.

FRED ARNOLD MANCHESTER.

Witnesses:

JOHN J. O'CONNELL,
DANA OSGOOD.
